COMBINATION ASH RECEPTACLE AND FLEXIBLE COVER

James Carl Hinkle, Huntington Park, Calif.

Application June 7, 1939, Serial No. 277,759

2 Claims. (Cl. 220—1)

This invention relates to improvements in ash receptacles and flexible covers and more particularly to the same for cigarette smokers.

The main object of the invention is to provide an ash receptacle and flexible cover of the above-mentioned character which is simple and durable in construction, reliable and efficient in use and inexpensive to manufacture.

Other objects and advantages of the invention will be apparent during the course of the following description.

In the accompanying drawing, forming a part of this specification and in which like numerals are employed to designate like parts throughout,

Fig. 1 is a front view of the improved receptacle,

Fig. 2 is a vertical sectional view taken on line 2—2 of Fig. 1,

Fig. 3 is a top sectional view taken on line 3—3 of Fig. 2,

Fig. 4 is a top view showing the flexible cover in a partially opened position and being operated by the thumb and forefinger of the left hand.

In the drawing, wherein for the purpose of illustration, I have shown a preferred embodiment of my invention, the numeral 5 denotes the hollowed, spherical-shaped, flexible cover having four fixed rib-like projections 6—6, 7 and 8, formed upon the outer surface, an elongated, normally-closed, opening or slit 9, two tubular snuffers 10—10 inserted through cover 5 at 11—11 and a centrally located circular aperture 12, through which is inserted the dish-shaped receptacle 13.

The ash receptacle 13 and base 14 are formed of sheet metal and spot-welded together at 15, after which flexible cover 5 is stretched over receptacle 13 in such manner as to provide substantially air-tight yet detachable engagement with surface 16.

The operation of the device is as follows:

Place the thumb and forefinger at the extremities of slit 9 and apply pressure in the direction of the arrows, as illustrated in Fig. 4, which causes the cover to open to admit the contents which fall into the metal receptacle 13, below. Upon removal of the pressure the cover closes, restricting the air-supply and extinguishing the burning objects as well as retaining the smoke and odor and excluding the debris from view. If not desirable to open the cover, the stubs may be inserted into snuffers 10—10, using the stubs to seal the device. Previous stubs may be pushed through the snuffers and into the inner

chamber with following stubs, thus keeping the device sealed at all times.

For the purpose of fully illustrating the usefulness of the fixed rib-like projections 6—6, 7 and 8 and, especially, the particular combination of ribs 6—6, receptacle 13 and base 14 the following explanation may be of use.

Certain strains or stresses are produced in the material of flexible cover 5 during the moulding, or by the moulding process, which are partially relieved by cutting slit 9 and which are further relieved by use and deterioration, thus preventing the proper and efficient closing of slit 9 at any time, thus rendering the device useless. Fixed rib-like projections 6—6, beginning near the center of the outer circumference, extending downwardly to and bearing upon opposite sides of base 14, as shown at 17—17, flex and reflex with each opening and closing of slit 9. The pressure of these ribs bearing upon the base 14 and backed by the outer surface 16 of receptacle 13, exert an upwardly and inwardly pressure to the upper half-portions of cover 5, resulting in the proper and efficient closing and sealing of slit 9 at all times. This closing feature may be accomplished by the use of springs or other improvised means but these add to the cost and are not satisfactory or reliable in use.

Rib-like projection 7, running in parallel relation to and surrounding slit 9 is for the purpose of causing the upper half-portions of the cover to properly align themselves when closing. Otherwise, unless the operator applies the pressure at the exact extremities of slit 9 and in the direction of the arrows as previously explained and illustrated in Fig. 4, the edges of slit 9 will not align themselves resulting in an unsightly whopper-jawed appearance as well as improper sealing.

The function of rib-like projection 8, running entirely around the outer circumference at the center will now be explained. When a burning object, such as the lighted stub of a cigarette, is dropped into the device and the device closed, the available supply of oxygen is quickly consumed and burning object extinguished, but in the meantime, other gases are formed raising the temperature of the inner chamber slightly but sufficiently to create a partial vacuum therein, when these gases cool or condense, with the result that when additional outside pressure is applied as at the extremities of slit 9, to open the device, these points partially collapse resulting in a very sudden opening of slit 9, a sudden inrush of outside air causing an undesirable

back-splash of ashes and other debris. Rib-like projection 8 is for the purpose of reinforcing the cover at this point and in relation to the surrounding material and prevent collapse at points of opening-pressure, insuring the proper opening of slit 9, and to give an additional springing action to cover 5.

The above condition does not occur when snuffers 10-10 are used in combination with flexible cover 5, but it is understood that the device may be made and used without the snuffers as well as other changes in size or shape without departing from the spirit of the invention or the scope of the subjoined claims.

It is to be understood that advertising matter may be placed on the outer surface of the cover 5.

Having thus described my invention, I claim:

1. The combination in a device of the class described comprising a dish-shaped ash receptacle and a base, said receptacle and said base being formed of relatively rigid material, and a hollowed, spherically-shaped cover formed of at least semi-flexible material, said receptacle being fixedly attached to said base, said cover having means for substantially air-tight yet detachable engagement between the outer surface of said

receptacle and the inner surface of said cover, said cover having two fixed rib-like projections on sides opposite each other and formed upon the outer surface thereof, said projections beginning near the horizontal equator of the cover and extending downwardly to and bearing upon opposite sides of said base.

2. In an ash receiver, a base, an ash receptacle in the form of a hollow segment of a sphere, 10 the receptacle making a substantially sharp angle with the base, and a resilient cover mainly in the form of a hollow sphere, the cover substantially conforming with the outer surface of the ash receptacle and having a portion thereof disposed in said angle between the receptacle and the base, the relative sharpness of the angle and the resilience of the material tending to maintain said portion of the cover in said angle, the upper portion of the cover having a slit that is normally closed, the slit being arranged to be opened by pressing the cover adjacent the ends of the slit, the receptacle resisting inward pressing of the portion of the cover opposite the receptacle, whereby to aid the cover in resuming its original shape when the pressing is released.

JAMES CARL HINKLE.
